**ELECTRICAL CABLE FOR A GASEOUS
DISCHARGE PANEL****Gerald E. Wojcik, Toledo, Ohio, assignor to
Owens-Illinois, Inc.**

Filed Mar. 15, 1971, Ser. No. 124,640

Term of patent 14 years

Int. Cl. D13—03

U.S. Cl. D26—5

FIG 1**FIG 2****FIG 3**

FIG. 4

FIG. 5

FIG. 1 is a front elevational view of an electrical cable for a gaseous discharge unit showing my new design; FIG. 2 is a rear elevational view thereof; FIG. 3 is an elevational view taken from one side thereof;

FIG. 4 is a front elevational view of a modified form of the electrical cable for a gaseous discharge unit shown in FIG. 1; and

FIG. 5 is a rear elevational view of FIG. 4.

I claim:

The ornamental design for an electrical cable for a gaseous discharge panel, as shown and described.
